UNITED STATES PATENT OFFICE

WILLIAM P. FAVORITE AND HARRY A. MOLER, OF DETROIT, MICHIGAN

DESIGN FOR A TRAFFIC MARKER

Application filed December 9, 1932. Serial No. 46,404. Term of patent 14 years.

To all whom it may concern:

Be it known that we, WILLIAM P. FAVORITE and HARRY A. MOLER, citizens of the United States of America, residing at Detroit, in the county of Wayne and State of Michigan, have invented a new, original, and ornamental Design for a Traffic Marker, of which the following is a specification, reference being had therein to the accompanying drawing forming a part thereof, in which

The dominant feature of our new design consists in providing on the top or exposed face of the traffic marker a design including advertising indicia, said design being produced in such a manner as to provide projections on the said face of the marker.

We claim:

The ornamental design for a traffic marker substantially as shown and described.

WILLIAM P. FAVORITE.
HARRY A. MOLER.
